UNITED STATES PATENT OFFICE.

EDWIN FRANCIS CRANE, OF BATAVIA, NEW YORK.

TRAY-BOARD.

SPECIFICATION forming part of Letters Patent No. 501,204, dated July 11, 1893.

Application filed June 27, 1892. Serial No. 438,220. (No model.)

To all whom it may concern:

Be it known that I, EDWIN FRANCIS CRANE, a citizen of the United States, residing at Batavia, in the county of Genesee and State of 5 New York, have invented a Tray-Board, a device for throwing and catching a ball, of which the following is a specification.

My invention relates to athletic sports and games, and the object of my invention is to 10 provide means for throwing and catching a ball, without touching it by the hand, in a game, to be played outdoors or indoors according to a code of rules.

The mechanism of my invention is illustrated in the accompanying drawings, in 15 which—

Figure 1 is a perspective view of the tray-board. Fig. 2 is a side-view of the same.

Like parts are designated by corresponding 20 letters of reference in both the figures.

The object of this invention is the production of a simple, serviceable and efficient device for catching and throwing a ball without touching the same with the hand; and it 25 consists, essentially, in the novel and peculiar combination of parts and details of construction as hereinafter first fully set forth and described and then pointed out in the claim.

30 A in the drawings represents a slender board composed of wood or other suitable material such as indurate fiber, prepared paste-board, papier maché, &c. The forward end of this tray-board A is leveled at a for end of the purpose hereinafter referred to.

The rear end of the tray-board is substantially semicircular and provided with a metallic guard or scoop B, having its upper edge b "wired" or otherwise strengthened, said 35 scoop being attached to the edges of the board A by screws, nails or other similar fastenings b'.

On the bottom side of the tray-board are provided two metallic sockets d, d', secured 40 to the board by suitable means, into which sockets are fastened wooden handles D D', by means of which the tray-board is manipulated in a manner hereinafter to be referred to.

In the better grades of these tray-boards I

shall nickel-plate the metallic portions of the 50 device and properly polish the wood-work thereof, but in the cheaper grades I may dispense with this plating, such changes being within the scope of my invention.

This device, which I call tray-board is designed for use in playing ball and its object is to both, catch and throw a ball, without handling the ball with the hand. In use the player takes hold of the handle D with his or her right hand and of the handle D' with 60 the left hand, holding the board in an upwardly-pointing position at an angle of about forty to fifty degrees (more or less as the case may be) for receiving a ball. In starting a game the ball is placed into the pocket B' 65 formed by the guard or scoop B and the tray-board depressed at its forward end so as to cause the ball to roll downward toward the forward end of the board. While the ball is thus rolling the player suddenly lifts the forward end of the board and by giving it a throwing motion gives an impetus to the ball which causes it to fly away the same as if it had been thrown by the hand. The opposite 70 player faces the first player and holding his tray-board in an upwardly inclined position tries to catch the ball upon the board when he suddenly elevates the rear end of the tray-board and catches the ball in the pocket B'. He then depresses the board and allows 75 the ball to descend and then proceeds to deliver the same as already described.

It will now be readily observed that it requires some practice to properly catch and throw a ball, which gives the game a certain 80 interest and which will make the game very popular.

In arranging a game of ball certain rules for throwing and catching the balls are to be followed and "points" allowed to, or forfeited by, the players, the score of which may be kept upon any suitable counter and in order to facilitate the playing of the game I have devised a set of rules for playing this tray-board, but such rules being empirical 90 and not imperative, I do not deem it necessary to here describe the same. I have also beveled the forward end of the board so that, 95

should a ball strike the ground before it reaches the player and roll along, the player may catch it by allowing it to roll upon the tray-board, the bevel assisting in the operation.

Having thus fully described my invention, I claim as new and desire to secure to me by Letters Patent of the United States—

An improved device for catching and throwing balls without handling the same by hand,

consisting, essentially, of a long and slender board having on its rear end a guard forming a pocket, and on its under side suitable handles for manipulating the device, substantially as described.

E. FRANCIS CRANE.
